Francis C. Huebner, ATTORNEY.

UNITED STATES PATENT OFFICE.

PETER C. SEEBERG, OF CLOVIS, CALIFORNIA.

PRESS FOR SETTING METAL FELLY WHEELS.

Application filed August 22, 1921, Serial No. 494,128.

To all whom it may concern:

Be it known that I, PETER C. SEEBERG, citizen of the United States, and resident of Clovis, in the county of Fresno and the State of California, have invented a new and useful Improvement in Presses for Setting Metal Felly Wheels, of which the following is a specification.

My invention relates to a press for setting metal rims in wheels in which the spokes have become loosened. It is generally known that at the present time automobile wheels are manufactured having pressed steel rims into which the ends of the wooden spokes of the wheel are fitted, and that in certain climates, and at certain seasons of the year the wooden spokes shrink in size and become loose in the rim. My device relates to a new and novel tool for tightening such spokes in the rim, or felly of the wheel by depressing a portion of the rim until it tightens around the end of the spoke.

I accomplish the object set forth, and other objects hereinafter set forth by means of the device hereinafter described and illustrated on the accompanying drawing, in which Figure 1 shows a perspective view of the tool complete attached to an upright post. Figure 2 is a perspective view of a set. Figure 3 is a perspective view of the die used with the set shown in Figure 2. Figure 4 is the base of the tool for holding the die. Figure 5 shows a part of a wheel indicating in section the spoke, the felly, and portions of the die press, the die and the set in active relation. Figure 6 is a modified form of set.

In said drawing B is an upright post to which a press C is attached. The press consists of a main support 4, having at the bottom thereof a base 9, and at the top a pivot support 4^a, a lever 2 pivoted at one end to support 4^a, a set guide 6, a set holder 5 which is adapted to operate in a slideway in guide 6, and a toggle link 3 pivoted at one end to handle 2 and at the other end to set holder 5. The set is shown as 8. The press C is assembled so that the set holder 5 can be moved vertically in line with base 9.

The die 10 is constructed of a tubular portion 10^a having a shoulder or outward projecting flange 11. The top 12 of the flange is adapted to be the face of the die and should be formed oval. The hole through the die is countersunk in the face of the die. This die is longitudinally cut in halves so it can be readily placed around the spoke of a wheel

as shown in Figure 5. The base 9 of the die press is formed annular with a section 9^a removed therefrom. The inside size of the base should readily receive the tubular portion 10^a of the die. The opening 9^a should be wide enough to admit a spoke.

The wheel, of which a fractional portion is shown in Figure 5, has spokes 13 which have tenons 13^a formed on the end thereof, and a rim 14 which has tubular projections 15 pressed therein which are adapted to receive tenons 13^a. The set 8 is constructed with the lower end tubular, the outside diameter fitting into the countersink 12^a, and the inside diameter being large enough to fit over the tubular projection 15. The set 8 is attached to the set holder 5. 7 is a set screw for holding the set on the set holder.

In operating this device the die is placed around the loosened spoke as shown in Figure 5 adjacent to the under surface of the rim of the wheel, and the set is then placed within the base 9 where the shoulder 11^a rests upon the top of the press base 9. The press is constructed so that when the wheel is in the position described on the press base, the set can readily be moved so it encircles the tubular projection into which the tenon of the spoke was inserted. When the rim of the wheel is thus between the die and the set described, it will be noted that by forcing the set adjacent to the face of the die the felly will be depressed around the spoke to meet the shoulder of the tenon 13^a. If it is desired to shrink the hole in the tubular projection 15, the set 18 shown in Figure 6 can be used in which the opening 8^a is formed tapering. Different forms of sets can be used.

It is also noted that instead of the press C described, the same results can be accomplished by using a hammer or other equivalent to actuate the set.

I claim as new and ask for Letters Patent: 1. A tool for tightening the spokes of a wheel having metal rims with tubular projections formed thereon into which ends of the spokes are inserted, consisting of a die having an opening therethrough adapted to fit around a spoke, said die having a flange thereon forming the face of the die, and a countersink in the face of the flange having a common center with the opening, the die being cut in halves along the line of the diameter of the hole, a die holder consisting of a ring with a sector cut away, the opening in

the ring formed by the cut-away sector being adapted to admit a spoke therethrough and the inside diameter of the ring being adapted to receive the die so that the flange of the die 5 will rest on the top of the ring, a set having an annular face adapted to fit around the tubular projection and within the countersink, and means for forcing the die and the set adjacent to each other.

10 2. A tool for tightening the spokes of a wheel having metal rims with tubular projections formed thereon into which ends of the spokes are inserted, consisting of a die having an opening therethrough adapted to 15 fit around a spoke, said die having a flange thereon forming the face of the die, and a countersink in the face of the flange having a common center with the longitudinal opening, the face of the die being formed oval, 20 the die being longitudinally cut in halves, a die holder consisting of a ring with a sector cut away, the opening in the ring formed by the cut-away sector being adapted to admit a spoke therethrough and the inside diameter of the ring being adapted to receive the 25

die so that the flange of the die will rest on the top of the ring, a set having an annular face adapted to fit around the tubular projection and within the countersink, and means for forcing the die and the set adjacent to each other. 30

3. A tool for tightening the spokes of a wheel having metal rims and wooden spokes, said spokes being fitted in tubular projections formed on said rim, consisting of a die 35 having an opening therethrough adapted to fit around the spoke where it enters the rim, and having said opening countersunk in the face of the die so that when assembled with the spoke an annular groove is formed within the face of the die around the spoke, said die being longitudinally halved, a press base adapted to hold the two parts of said die rigidly together, a tubular set adapted to encircle said tubular projection, and to engage 40 said annular groove in the die, and means for forcing the set adjacent to the face of the die, substantially as described. 45

PETER C. SEEBERG.
